UNITED STATES PATENT OFFICE.

EUGEN LINNER, OF BUDAPEST, HUNGARY.

BOTTLE STOPPER.

Application filed July 31, 1926, Serial No. 126,208, and in Hungary November 10, 1925.

My invention relates to bottle-stoppers comprising an expansible plug adapted to be pressed, by means of a screw, against a body supported by the edge of the bottle-mouth, such longitudinal compression of the plug causing hermetic engagement between the bottle-neck and the plug owing to the transverse expansion of the latter.

The object of the invention is to provide a simple and convenient construction, in which especially the screw-bolt is prevented from dropping into the bottle, with the parts assembled in such a manner that the expansible plug, if worn or damaged, may be replaced without using any tool. In order to cause the screw-bolt, when entirely unscrewed, to be caught by the body supported by the edge of the bottle-mouth, I enlarge the threaded end portion of the bolt over the width of the central opening provided in said body for the reception of the screw-bolt, and, in the side of the body supported by the bottle-mouth, I provide an aperture which will allow the screw-bolt to be introduced laterally.

A constructional form of the invention is shown, by way of example, in the accompanying drawings in which—

Fig. 1 is a sectional elevation of my improved bottle-stopper;

Fig. 2 is a plan view of the same;

Fig. 3 is a detail view showing a bow forming the wings for operating the screw-nut;

Fig. 4 is a central longitudinal section of the body supported by the edge of the bottle-mouth and against which the plug is pressed in order to be expanded;

Fig. 5 is the plan of the same body with the moiety cut in a horizontal plane.

The expansible plug consists of a rubber ring 1 surrounding the unthreaded portion of the screw-bolt 2 which is provided with a large head at its inner end. The body against which the plug 1 is pressed consists of a metal cap 4 with a rim or flange resting on the edge of the bottle-mouth. The nut 3 for operating the screw is located within the cap 4. Wings for operating the nut 3 are formed by a bow 6 which is secured by means of a pivot 5 so that it may be laid down as indicated in Fig. 2 by dotted lines.

According to the invention, the threaded end of the bolt 2 has a somewhat larger diameter than the plain portion thereof,

the central opening 7 in the bottom of the cap 4 having a diameter between those of the plain and threaded portions of the bolt 2. In order to enable the bolt 2 to be introduced into the opening 7, I provide the cap 4 with a lateral aperture 8, Fig. 4, having a width surpassing the diameter of the threaded portion of the bolt 2 and being connected with the central opening 7 by a radial slot 9 in the bottom of the cap 4, Fig. 5, the width of this slot corresponding to the diameter of a short neck 10 of the bolt 2 close below the threaded portion.

What I claim is—

1. A bottle-stopper consisting of a body supported by the edge of the bottle-mouth and projecting into the bottle-neck and having a central opening, a bolt fitting into said central opening and having a head at its inner end and a threaded portion at its outer end with a diameter greater than that of said central opening, an expansible plug upon said bolt between its head and said body, and a nut adapted to be screwed upon the threaded end portion of said bolt, a lateral aperture provided in said body and connected with said central opening allowing said bolt to be laterally introduced into said central opening.

2. A bottle-stopper consisting of a metal cap having a rim resting on the edge of the bottle-mouth, a cylindrical side wall projecting into the bottle neck, and a flat bottom provided with a central opening, in combination with a bolt fitting into said central opening and having a large head at its inner end, a threaded portion at its outer end with a diameter greater than that of said central opening, and a short neck portion formed below said threaded portion with a diameter smaller than that of said central opening, a rubber ring upon said bolt between its head and the bottom of said cap, and a screw-nut fitting upon the threaded end portion of said bolt, said cylindrical side wall of said cap being provided with an aperture so formed as to allow said threaded end portion of said bolt to pass through and connected with said central opening by a radial slot of such a width as to let through only the neck portion of said bolt.

In testimony of which I hereunto affix my signature.

EUGEN LINNER.
